UNITED STATES PATENT OFFICE.

JOSEPH S. SEAMAN, OF PITTSBURG, PENNSYLVANIA, ASSIGNOR TO HIMSELF,
JAMES B. YOUNG, AND ROBERT SLEETH, ALL OF SAME PLACE.

SPLICER-BAR FOR RAIL-JOINTS.

SPECIFICATION forming part of Letters Patent No. 276,900, dated May 1, 1883.

Application filed January 27, 1883. (No model.)

To all whom it may concern:

Be it known that I, JOSEPH S. SEAMAN, a citizen of the United States, residing at Pittsburgh, county of Allegheny, State of Pennsylvania, have invented or discovered a new and useful Improvement in Splice-Bars for Rail-Joints; and I do hereby declare the following to be a full, clear, concise, and exact description thereof, reference being had to the accompanying drawings, making a part of this specification, in which—like letters indicating like parts—

Figure 1 is a top plan view of a rail-joint illustrative of my present invention; and Figs. 2 and 3 are transverse sectional views of the rail, showing the splice in end elevation.

My invention relates to certain improvements in rail-joints and in the construction of splice bars therefor; and it consists, in general terms, of a splice-bar for such joint of rail form, having the flange on one side "set up" to lap over or onto the flange of the rail proper, and also by preference having a groove in the side edge of the head adapted to receive the adjacent edge of the rail-head, and in certain combinations of such splice-bar with the rails, and with means for securing them together, as hereinafter more fully described and claimed.

In rolling railroad-rails, especially of steel, it is customary to cut off two or three feet from each end to insure perfectly sound metal in the rail. These crop-ends, together with defective rails, always produced to some extent, have heretofore been considered waste products and practically worthless, except for purposes of reworking, at a considerable expense, into other articles, or for remelting.

The purpose of my present invention is to utilize such crop-ends and defective rails to better advantage and by cheaper methods than heretofore, by making them into splice-bars for rail-joints, and thereby secure not only economy, but also a superior construction of bar and joint.

In making my improved splice-bar the crop-ends and defective rails, having a form in cross-section the same as the rail, but of varying lengths, are, while still hot, passed through suitably-grooved rolls to set up or raise up one side flange of the foot, forming a recess in the bottom corresponding to the rail-flange,

so that the former may overlap the latter and rest thereon, with the other or unbent flange resting on the tie; and in the same pass I prefer to roll a groove in the side edge of the head, 55 adapted to receive the adjacent edge of the rail-head. This work may be done by suitably-grooved rolls, either in one or in several passes, and, when done, the crop-ends or rails so shaped are cut or sheared into the desired 60 lengths for splice-bars. These features of construction are illustrated in the drawings, in which—

A A represent portions of two rails secured in the usual manner to cross-ties B B.

My improved splice-bar is represented at C combined with the rails for the purpose of effecting a joint. In general form it is similar to the rails, and its length is equal to the distance between two ties, so that its ends may 70 rest upon and be secured to the same, as presently described. One side flange, c', of the splice-bar is set up by rolling, as before described, (see Figs. 2 and 3,) forming a depression or recess in the bottom face of the foot corresponding to the side flange a of the rail, so 75 that the flange c' may overlap and rest upon flange a, with the other side flange, c, of the splice-bar resting flat upon the face of the ties. I also form by preference a groove, c², 80 along the side edge of the splice-bar, adapted in size and form to receive the adjacent edge of rail-head a', (see Fig. 3,) and thereby bring the bar and rail into closer relationship and 85 lock them more effectually against vertical displacement.

In forming joints the splice-bar C is placed on or against the outside of the rails and bolted thereto by the usual bolts, e, in any desired number. The splice-bar is also secured to the ties 90 along its side c by any desired number of spikes b b', the latter being represented as driven through notches cut in the flange. I also prefer to drive spikes b² at the ends of the splice-bar, (see Fig. 1,) which are turned so as 95 to incline the spike-heads inward and cause them to bear upon the flange c'. The bolts e and lapping flanges a c' will form a rigid and secure connection between the rail ends sufficient for ordinary purposes; but by matching 100 the head a' into the groove c² such connection is materially strengthened and improved, both

by affording greater overlapping surface between the flanges and shorter bolt-connections, also by the interlocking engagement which is made thereby between the heads. If still greater security is desired against vertical movement between the rails and splice-bar, a block, e' , Fig. 2, may be placed in the inclosed space between the rail ends and splice-bar and held therein by the bolts e . This block, bearing upon the flange e' below and heads of the rails and splice-bar above, will supplement the connection made by the bolts and flanges and add materially to the security of such connection. This block e' may be used either with or without the grooves c^2 , though with such grooves there will be less occasion for its use. It may be made either of suitable length to be inserted between bolts e , or it may be longer and provided with bolt-holes adapted to register with the holes in the rail ends and in the splice-bar.

If desired, the usual or any suitable form of fish-plate or splice-bars may be used on the inside of the rails; but ordinarily they will not be needed.

By this improvement I not only utilize the waste product of rails with trifling expense in fitting, but I also secure a very strong and safe joint-connection. Also, by employing a splice-bar of rail form and of the same height as the rails, the joint is bridged by a short section which carries the wheels, and thus prevents battering the rail ends, and this advantage is secured without cutting into the rails, thereby weakening them and adding materially to the expense of manufacture as commonly practiced heretofore, where attempt was made to bridge the rail ends with the splice-bar. These features of utility, cheapness of construction and

fitting, and the profitable use made of waste material are important considerations, and outweigh the value of the material employed, especially considering the expense necessarily involved in working it over into other forms or remelting it.

I claim herein as my invention—

1. A splice-bar, C, of rail form, having one flange, e' , set up or raised above the plane of its other flange, to overlap the rail-flange, substantially as set forth.

2. A splice-bar, C, of rail form, having one flange, e' , raised or set up above the plane of the other, and having a groove, c^2 , formed in the side edges of its head, substantially as and for the purposes set forth.

3. In combination with rails A A and ties B B, a splice-bar, C, of rail form, having one flange, e' , set up or raised to overlap the flange a of the rails, and bolts e , substantially as set forth.

4. A rail-joint having in combination rails A A, bolts e , and splice-bar C, the latter being of rail form, with one flange, e' , raised to overlap the flange a of the rails, and grooved along its side edge c^2 , to receive the head of the rails, substantially as set forth.

5. The splice-bar C, of rail form, having one flange, e' , raised above the plane of the other, in combination with rails A A, bolts e , and inclosed block e' , substantially as and for the purposes set forth.

In testimony whereof I have hereunto set my hand.

JOSEPH S. SEAMAN.
